CLAIM

The ornamental design for hair straightening apparatus, as shown and described.

DESCRIPTION

FIG. 1 is a perspective view from above to the left and to the front of the hair straightening apparatus, which is the subject of my new design;

FIG. 2 is a perspective view from above, to the left and to the rear of the hair straightening apparatus;

FIG. 3 is a top plan view thereof;

FIG. 4 is a bottom plan view thereof;

FIG. 5 is a left side elevational view thereof;

FIG. 6 is a right side elevational view thereof;

FIG. 7 is a front elevational view thereof; and,

FIG. 8 is a rear elevational view thereof.

In the drawings, the portions shown in dotted lines form no part of the claimed design.
